(57) **CLAIM**

The ornamental design of a bezel and user interface for audio/video equipment, as shown and described.

DESCRIPTION

FIG. 1 is a perspective view of a bezel and user interface for audio/video equipment showing our new design;

FIG. 2 is front elevational view thereof;

FIG. 3 is a left side elevational view thereof;

FIG. 4 is a right side elevational view thereof;

FIG. 5 is a top plan view thereof;

FIG. 6 is a rear elevational view thereof;

FIG. 7 is a front perspective view of a second embodiment of FIG. 1;

FIG. 8 is front elevational view of FIG. 7;

FIG. 9 is a left side elevational view of FIG. 7;

FIG. 10 is a right side elevational view of FIG. 7;

FIG. 11 is a top plan view of FIG. 7; and,

FIG. 12 is a rear elevational view of FIG. 7.

The broken lines in the drawing are for illustrative purposes only and forms no part of the claimed design.
